Albert A. Bumbaugh, ^{Inventor}

By H. G. Burns

Attorney

UNITED STATES PATENT OFFICE.

ALBERT A. BUMBAUGH, OF WARSAW, INDIANA.

FENCE.

Application filed February 3, 1922. Serial No. 533,827.

To all whom it may concern:

Be it known that I, ALBERT A. BUMBAUGH, a citizen of the United States of America, and resident of Warsaw, in the county of Kosciusko and State of Indiana, have invented certain new and useful Improvements in Fences, of which the following is a specification.

This invention relates to improvements in fences wherein a series of wire strands are supported by structural iron posts, and the objects thereof are, first, to construct the posts so that the wire strands may be secured and held in connection therewith without additional fastening means ordinarily employed; and second, to provide a fence structure that may be installed upon the surface of the ground without the necessity of digging post holes.

10 The above objects are accomplished by the construction illustrated in the accompanying drawings in which:—

Fig. 1 is a side elevation of a post embodying the present invention;

25 Fig. 2 is a front elevation projected from Fig. 1;

Fig. 3 is a plan view projected from Fig. 1;

30 Fig. 4 is a side view of the foot plate for the post and including an anchor screw for holding the same in place;

Fig. 5 is a plan view of a fence embodying the invention; and

35 Fig. 6 is a detail view showing a portion of the post in modified form.

The characters appearing in the description refer to parts shown in the drawings and designated thereon by corresponding characters:—

40 The invention comprises a post 1 of angle iron, the lower end of which is flattened and bent to form a horizontally disposed foot 2 which is riveted onto a foot plate 3 so that the post is held in an upright position at one 45 end of the foot plate. An opening 4 in the foot plate is made through which an anchor screw 5 is driven into the ground for holding the post in place.

In the angle of the post 1 are made a 50 series of straight slots 6, obliquely the higher end of each terminating with a descending notch 7 and the lower end thereof ter-

minating with an ascending notch 8. The slots are made of sufficient width as to admit of the insertion therethrough of the wire 55 fence strands 9 into the notches when the strands are positioned at a slant corresponding with the slot. The notches are so proportioned and positioned relative to each other as to permit the strands to extend 60 therethrough in horizontal planes.

In the form shown in Fig. 6 the post 1' has slots 6' similar to those in the former instance, but differ therefrom in that the alternate slots slant in opposite directions. 65 In this manner any tendency of the post to incline, due to uniform obliquity of the slots is obviated inasmuch as the alternate slots counteract any tendency of the other slots to an equal degree.

70 In the construction of a fence embodying the invention, the foot plates 3 are set alternately on the opposite sides of the fence as shown in Fig. 5 so that the strands 9 of the fence are braced against pressure that may 75 be applied from both sides thereof. If desirable, at a fence corner, or at the end of a fence a post provided with an enlarged foot plate 10 may be employed and anchored in the customary manner of securing end and corner posts, or with screw anchors 5 where the soil is of sufficient solidity to sustain the tension of the fence.

75 In constructing a fence in which the present invention is employed it is not necessary to secure the foot plates with anchor screws where the posts are located on a hill or upon a level, except an occasional post where the fence is of great length, or, the post is located in a ravine or depression in the ground, or at the end of the fence where the strain 80 upon the post is in one direction only.

85 By constructing the posts with straight slots the ends of which have horizontally aligned notches, the strands of the fence 90 may be securely attached to the posts without resorting to the various fastening means and incidental labor occasioned by usual methods, and thus, the building of a fence is facilitated and economy effected.

100 What I claim is:—

A post for a surface fence, comprising an angle iron upright, the lower end of which is flattened and bent at a right angle form-

ing a horizontal foot, there being a series of straight slots formed in the angle of the upright above the flattened portion, each slot being obliquely disposed and there being formed at the upper end of each slot a descending notch and at the lower end thereof an ascending notch, said notches being horizontally alined; and a foot plate rigidly se-

cured to the bent portion of the upright, and having an anchor hole therein. 10

In testimony whereof I affix my signature, in presence of two witnesses.

ALBERT A. BUMBAUGH.

Witnesses:

M. L. TCHENOW,
PEARL KLECKNER.
